TOE FIXTURE FOR A SKI SAFETY BINDING

Michio Iizuka, Tokyo, Japan, assignor to
Hope Kabushiki Kaisha

Filed Apr. 15, 1974, Ser. No. 460,686

Claims priority, application Japan Oct. 20, 1973

Term of patent 14 years

Int. Cl. D21—02

U.S. Cl. D34—14 D

FIG. 1

FIG. 2

FIG. 3

FIG. 4

FIG. 5

FIG. 6

FIG. 1 is a front elevational view of a toe fixture for a ski safety binding showing my new design;

FIG. 2 is a rear elevational view thereof;

FIG. 3 is a top plan view thereof;

FIG. 4 is a bottom plan view thereof;

FIG. 5 is a left side elevational view thereof; and

FIG. 6 is a right side elevational view thereof.

I claim:

The ornamental design for a toe fixture for a ski safety binding, substantially as shown.
